UNITED STATES PATENT OFFICE.

JACOB HITZERT, OF SAGINAW, MICHIGAN.

RAIL ATTACHMENT.

1,426,192.

Specification of Letters Patent. Patented Aug. 15, 1922.

Application filed April 5, 1922. Serial No. 549,676.

To all whom it may concern:

Be it known that I, JACOB HITZERT, a citizen of the United States, residing at Saginaw, in the county of Saginaw and State of Michigan, have invented new and useful Improvements in Rail Attachments, of which the following is a specification.

My present invention pertains to railway rail fastening devices and it contemplates the provision of means whereby opposing rails are securely held to their ties and this without the necessity of driving bolts or other fastening elements through the base of the rails.

15 The invention further contemplates the provision of means whereby lateral creeping of the rails with respect to the ties is eliminated.

The invention in all of its details will be 20 fully understood from the following description and claims when the same are read in connection with the drawings accompanying and forming part of this specification, in which:

25 Figure 1 is a top plan view of several railway ties showing rails attached thereto by means of my novel fastening device but with the means for fastening the device to the ties eliminated.

30 Figure 2 is a transverse sectional view of a tie and rail secured thereon.

Figure 3 is a top plan view of one of the fastening plates.

Figure 4 is a side elevation thereof.

35 Figure 5 is a top plan view of one series of rails and showing the rail web supports.

Figure 6 is a side elevation of the plate that rests against the web of the rails.

40 Figure 7 is a sectional view of the style of dog I employ to brace the rails at the curve.

Figure 8 is a top plan view of the block that receives the supporting plate illustrated in Figure 3.

45 Figure 9 is a view illustrating a portion of the dogs that brace the rail.

Similar numerals of reference designate corresponding parts in all the views of the drawings except in the modified construction of brace illustrated by Figure 6.

50 The ties 1 of my novel construction are preferably formed of cement or like material and adapted to be securely retained at a point adjacent the ends of the ties are blocks 3 in which I provide a central aperture 3^a and the said blocks are preferably

dipped in creosote in order to prolong the life thereof, and adapted to rest upon the ties 1 are plates 4 of the construction clearly indicated by Figure 3. These plates 4 are 60 bolted or otherwise secured to the ties by means of the fastening members 14 and the said plates preferably are provided with one or more bolt receiving apertures at their ends to permit of proper adjustment of the 65 plates with respect to the ties and the said plates 4 are provided with the recesses of the configuration shown in Figure 3 and indicated by the square nut receiving opening 5 and the practically semi-circular bolt receiving portion 7 as well as the nut-confining lug 6. The plate 4 is further provided in the center thereof with a downwardly extending lug or projection 8 that is adapted 70 to enter and be firmly retained in the apertures 3^a of the block 3 and this construction assists in preventing end-wise or other slipping of the plate 4 with respect to the tie 1. The plate 4 is further provided near its ends with the key-way slot 11, that is adapted to 75 receive the end 10 of the dog 9. The slot 11 assists the bolt 13 in holding the dog in proper position on the plate 4 and in order to prevent casual displacement of the dog 9 I provide a well or chamber 12 that receives the nut of the bolt 13. The dog 9, as will be seen, by reference to Figure 2 in particular, bears at its inner end against the web of the rail 2 and its lower inner surface is so constructed that it conforms to the configuration of the base of the rail and said 80 dog is held slightly above the portion 6 of the plate 4 due to the outer pointed construction 10 thereof. It will be seen that this space will assist in taking up vibration 85 during passage of cars over the rail and thereby prolong the life of the connecting elements of the invention. The square openings at the ends of plate 4 are to permit fastening elements or bolts to pass there- 90 through.

In Figure 6 I illustrate more or less of a modified form of rail bracing member and this form is substituted for the dog 9 at the points where the rails are joined one to the other and comprises all of the elements of the dog 9 and in addition the connecting portion 9^b that rests against the web 9^a of the rails. In Figure 7 I illustrate the dog 9 having the upwardly extending portion 110 9^c and this particular form of dog is employed on curved track rails.

It will be gathered from the foregoing that in order to secure my rail fastening means to the ties 1 it is simply necessary to place the plate 4 with its projection 8 resting in the aperture 3^a of the block 3 and then tighten up the nut on the bolt 14. The rail is then properly positioned on the plate and the bolt 13 seated in the portion 7 of the plate with the shank of the bolt extending 10 through the aperture 12 of the dog 9. The nut is then tightened up on the bolt 13 which will firmly hold the rail to the tie. From this it will be gathered that it is absolutely unnecessary to bore either the web or base 15 of the rail, even at the point where the rails are joined to each other as at such points I substitute the connecting portions 9^a of the dogs 9.

It will be gathered from the foregoing 20 that my invention not only eliminates the use of fish-plates but at the same time provides a device for connecting the rails that may be employed without the necessity of in any way weakening the rail by drilling the 25 same and the device further assures the rails from spreading but on the other hand makes ample provision for vibration and at the same time allows for removal or substitution of any portion of the device with but 30 a small amount of effort on the part of those employing the device.

If wooden ties are substituted for composition tie 1, spikes may be employed in lieu of bolts 14.

Having described my invention, what I 35 claim and desire to secure by Letters-Patent is:—

1. In rail fastening means, the combination of a plastic tie, a block of suitable material anchored in each end of the tie, said 40 block having a recess therein, a plate adapted to rest upon and be secured to the tie and having a projection that rests in the aperture of the block, a bolt and nut receiving aperture formed in the plate adjacent the projection and on each end of the plate, transverse kerfs formed in the plate and a 45 dog having a chamber and aperture to receive bolts whereby the dog is secured to the plate; said dog having one end that bears against the web of a rail and having the other end seated in one of the kerfs of the plate.

2. In means for the purpose set forth, the combination of ties formed of plastic material, a block anchored in each end of each tie, an aperture formed in the block, plates having projections adapted to enter the blocks, means formed in the plates for securing the plates to the blocks, dogs adapted to bear at one end on the plates and at the other end against the web and base of a railway rail; said dogs having a portion formed integral and extending from one dog to the dog on the adjacent plate and rail, and means formed on the plates for retaining the dogs in proper position with respect to the plates and rails. 55 60 65

3. In means for securely holding railway rails at the proper gauge with respect to each other, the combination of plastic ties, blocks anchored in the ties, plates resting on the blocks and ties and rigidly secured thereto, dogs superimposed on the plates and secured thereto and means for securing the dogs on the plates, said plates comprising a flat central surface to receive the base of a rail, chambers having square outer ends and elongated inner ends, the elongated portion extending upwardly and toward the 75 square portion to form a bolt-head confining chamber, and kerfs formed in the ends of the plates at the outer end of the square portion of the chambers. 80

4. In means for the purpose set forth, the combination of a tie, plates mounted thereon and having kerfs on the ends thereof and bolt-receiving chambers arranged adjacent the kerfs, flat portions formed on the plates to receive the base of railway rails and dogs 90 having pointed outer ends adapted to enter the kerfs of the plates and their inner ends to bear against the web of the rails; said dogs having their inner, lower surface constructed to conform to and bear against the 95 base of the rails and having the remaining portion of their lower walls inclined toward the pointed end thereof, substantially as and for the purpose specified.

In testimony whereof I have hereunto set 100 my hand in presence of two subscribing witnesses.

JACOB HITZERT.
